TYPEWRITING MACHINE

Original Filed July 12, 1923

2 Sheets-Sheet 2

UNITED STATES PATENT OFFICE.

LEWIS C. MYERS, OF FREEPORT, AND GEORGE F. HANDLEY, OF GLENDALE, NEW YORK,
ASSIGNORS TO ROYAL TYPEWRITER COMPANY, INC., OF NEW YORK, N. Y., A COR-
PORATION OF NEW YORK.

TYPEWRITING MACHINE.

Original application filed July 12, 1923, Serial No. 641,073. Divided and this application filed April 21, 1924. Serial No. 707,895.

To all whom it may concern:

Be it known that we, LEWIS C. MYERS, a citizen of the United States, and resident of Freeport, in the county of Nassau and State of New York, and GEORGE F. HANDLEY, a citizen of the United States, and resident of Glendale, in the county of Queens and State of New York, have invented certain new and useful Improvements in Typewriting Machines, of which the following is a specification.

This application is a division of our prior application, Serial No. 641,073, filed July 12, 1923.

15 The machine illustrated in the parent application is designed for a special class of work in which relatively narrow slips of paper are employed and wherein it is necessary that each succeeding sheet be fed into the machine in exactly the same position and be held accurately while being written upon. Certain paper feeding devices were devised for use therewith, but are in no way limited in their applicability to the 20 particular machine disclosed in the parent application, or to any specific type of machine, but have a broad field of application.

An object of the invention is the provision of a simple and efficient feed roll mounting wherein front and rear feed rolls are carried by the same frame and will be spring pressed against the platen in such a manner that both will engage the platen 35 even if the thickness of the sheets varies.

Another object is the provision of a mounting for the paper table which is intimately associated with the feed roll support and is simple and efficient.

40 Another object is the provision of a paper table or chute having one side adjustable in order that the width thereof may be varied, while the paper table as a whole may be adjusted from side to side of the 45 machine without varying the adjustment of the width of the chute itself.

Another object is the provision of a paper holding finger at the front of the machine which will engage the paper above 50 the printing line and from side to side of the printing point.

Other objects will be apparent from the

following detailed description and the appended claims.

In the drawings:

Figure 1 is a front view of a carriage of a typewriting machine showing certain portions of our invention.

Figure 2 is a vertical fore-and-aft section with parts in elevation.

Figure 3 is a plan view of the paper table and feed rolls with the frame therefor, the platen being removed.

Figure 4 is a view similar to Figure 2 but on an enlarged scale.

There is illustrated a carriage having side members A and a base member B between which and a track member C are interposed ball bearings a. This track member C may be a part of the main frame, or it may be a part of the shift frame as in the case of the ordinary Royal typewriter structure. In the carriage is mounted a platen D which is illustrated as a short platen, as in the parent case, but so far as the invention herein contained is concerned, it may be of any desired length. This platen is provided with the usual or any desired line space mechanism E. The usual paper scale F and fingers G may be employed and the scale 70 is supported by fingers H carried by the member C. One of the fingers G is usually omitted or moved to inoperative position to permit the use of a special finger herein-after described. These parts may be of the 75 usual Royal construction or of any other old or desired form.

A rod 1 extends between the side plates A of the carriage and has mounted thereon arms 2 which carry a short shaft 3 in their ends. Arms 4 are carried on the shaft 3 inside of the arms 2 and support at their ends rear and front feed rolls 5 and 5'. The shafts of these rolls are preferably mounted in open bearings in the ends of the 95 arms 4 as shown in Figure 4. Each arm is provided with an outwardly extending ear 6 to each of which is hooked one end of a spring 7 the other end of which is fastened to a pin 8 supported by the side plates A 100 of the carriage. These springs tend to hold the feedrolls against the platen D.

A flat bar 9 which is preferably integral with the arms 2, overlies the rod 1 and sup-

ports a paper table 10. Collars 11 integral with arms 2 are provided with set screws for positioning and securing the arms to the pivotal rod 1. The paper table 10 extends beneath the platen and has cut outs through which the feed rolls 5 and 5' pass to contact with the platen. Its upper portion has a relatively high side portion 12 fixed thereto and a right hand portion 12' similar in shape but adjustably mounted on the main portion by means of bolt and slot connections 13, which permit the adjustment of this side to the dotted line position in Figure 3. By the use of these relatively high side portions a deep chute is formed, the width of which may be adjusted so that the bills or sheets upon which writing is being done will fit snugly in the bottom thereof. Successive sheets or bills may therefore be introduced and the writing in the right hand column will always fall in the proper position. The table 10 and sides 12 and 12' have rolled edges 14 to improve the appearance and facilitate the introduction of the bills into the machine.

To hold the bills snugly in the bottom of the chute, one of the usual paper fingers G is either omitted or turned to inoperative position and a special finger provided. This comprises a member 16 which is pivotally connected to one of the arms or fingers H and is spring pressed against the platen by a spring 17. It extends over the printing point adjacent to the finger G and has a cut-out 18 lying above the printing point. An upper extension has a rolled end 19 and the lower edges 20 are outturned in order that they may not catch on the sheets when introduced into the machine.

It will be noted that the paper table and chute can be adjusted as a whole or the size of the chute can be varied, and that either adjustment can be made without interfering with the other. The feed rolls and table are pressed into position by simple spring mechanism and the rolls are so mounted that they will always bear evenly against the platen. The special paper finger 16 holds the paper closely against, above and at both sides of the printing point, while the scale F performs the same function below the printing line. The paper is therefore held smoothly at the point of printing, even if a stiff sheet or card is employed. Since the scale F and finger 16 is supported by the frame or by the shift frame if the machine is so equipped, it will always bear against the paper in the same relative position to the printing point regardless of the endwise position of the carriage or the case shift position.

Obviously various detail changes may be made without in any way departing from the spirit of the invention, and it is understood that the invention is to be regarded as

limited only by the scope of the appended claims.

We claim as our invention:

1. In typewriting machines, a carriage having side plates, a rod extending between the side plates, a paper table carried by said rod, arms on said rod, a rod in the free ends of said arms, short arms on the second rod, and feed rolls carried thereby.

2. In typewriting machines, a carriage having side plates, a rod extending between the side plates, arms thereon carrying feed rolls, a cross bar integral with said arms, and a paper table supported on said cross bar.

3. In typewriting machines, a carriage having side plates, a rod extending between the side plates, arms thereon carrying feed rolls, a cross bar integral with said arms, a paper table supported on said cross bar, and springs connected with the arms and carriage side plates and holding the feed rolls and paper table against the platen.

4. In typewriting machines, the combination with the platen of an upright support disposed in front of the platen, stationary relative to the movement of the platen and terminating adjacent the printing line, and a paper holding finger hinged to said support and extending laterally over the printing point and having a notch in its lower edge to permit passage of the type bar, said finger being spring-pressed against the platen.

5. In a typewriting machine, the combination with the platen of an upright support disposed in front of the platen and stationary relative to the movement of the platen, and a paper holding finger hinged to said support and extending laterally past the printing point and thereabove, said finger having a notch in its lower edge to permit passage of the type bar and an upwardly extending portion to press the paper against the platen.

6. In a typewriting machine, the combination with the platen of an upright support disposed in front thereof and stationary relative to the movement of the platen, and a paper-holding finger hinged to said support and extending laterally past the printing point, said finger having a notch in its lower edge to permit passage of the type bar, the portions of the finger adjacent said notch being turned outwardly, and a spring for pressing said finger against the platen.

7. In a typewriting machine, the combination of a supporting rod, a paper table extending under the platen and having high outwardly sloping sides, one of which is adjustably carried by the other in order that the bottom of the table may be set to the exact width of the paper employed, and means supporting said table on said rod and

permitting its adjustment bodily to bring it into any desired relation to the letter spaces of the carriage.

8. In a typewriting machine, the combination of a supporting rod carried by the carriage, a paper table extending under the platen and having high outwardly sloping sides, one of which is adjustably carried by the other in order that the bottom of the table may be set to the exact width of the paper employed, means holding said side in

adjusted position, means supporting said table on the rod and permitting its adjustment bodily without varying the adjustment of the side of the table, and means holding the table in any desired position of adjustment. ¹⁵

In testimony whereof we have hereunto subscribed our names.

LEWIS C. MYERS.

GEORGE F. HANDLEY.
